UNITED STATES PATENT OFFICE.

JAMES H. COOPER, OF DETROIT, MICHIGAN, ASSIGNOR, BY MESNE ASSIGNMENTS, TO
McCORD RADIATOR & MFG. CO., OF DETROIT, MICHIGAN, A CORPORATION OF
MAINE.

THERMOSTAT FOR RADIATORS.

Application filed November 10, 1922. Serial No. 600,010.

To all whom it may concern:

Be it known that I, JAMES H. COOPER, a subject of the King of Great Britain, residing at Detroit, in the county of Wayne 5 and State of Michigan, have invented new and useful Improvements in Thermostats for Radiators, of which the following is a specification.

This invention relates to thermostatic 10 valve devices for radiators for internal combustion engines:

One object of my invention is to provide a thermostatic valve device which, when the water or cooling medium in the cooling system 15 is cold, will not cut out the entire radiator and allow it to freeze in cold weather before the thermostatic valve opens to cut in the radiator as heretofore, but allows a portion of the radiator core to remain in 20 circulation with the cylinder block when the valve is closed and thus permit the cooling medium to be warmed up more quickly on starting the engine by being required to handle only a part of the entire amount of 25 water in the radiator.

A further object of my invention is to locate the thermostat in the flow to the motor through that part of the radiator left 30 in circulation with the cylinder block when the valve is closed so that said valve will be opened as soon as the water in the flow is warmed by the engine and cut in the entire radiator before waiting until all the water 35 therein is warm enough to operate the thermostat and open the valve.

Another object of my invention is to divide the core into front and rear circulating sections and to have the thermostatic device 40 cut out the rear section when the water is cold, so that the rear section will be warmed by the heat radiated from the warm water circulating through the front section and also by the air being warmed by the front section before passing over the rear section, 45 thus preventing freezing of the rear section before the entire radiator is placed in circulation, and avoiding the necessity or excuse for the use of radiator curtains or the more expensive radiator shutters.

50 The invention consists further in the matters hereinafter described and more particularly set forth in the appended claims.

In the accompanying drawings—

55 Fig. 1 is a front view of an assembled radiator provided with a thermostatic device

of my invention, a portion of the upper part of the radiator being cut away to show the device;

Fig. 2 is an enlarged fragmentary vertical sectional view taken on line 2—2 of Fig. 1, 60 the valve being shown closed;

Fig. 3 is a similar sectional view of the same parts with the valve open; and

Fig. 4 is a horizontal sectional view taken 65 on line 4—4 of Fig. 2.

The radiator shown in the drawings comprises a core 1 contained within an outer metal shell or casing 2. These parts are made and assembled in accordance with the usual radiator practice. The core, through 70 which the cooling medium circulates, has the usual upper and lower tanks and interposed water conduits, these being corrugated when the core is of the cellular type and in the form of vertical tubes when the core is 75 of the fin and tube type. It is immaterial to my invention whether the core is of one type or the other, although for illustrative purposes I have shown the fin and tube type in the drawings. The tubes are indicated 80 by 3, the horizontal fins by 4, and the upper tank by 5.

The thermostatic device of my invention, when arranged as in the drawings, is located in the upper tank 5. It has a casing 85 6 with an inlet pipe or hose connection 7 extending outside of the rear wall 8 of said tank. In the casing 6 are two upright partition walls 9, 10, arranged substantially parallel and being integrally connected with 90 the bottom wall 11 of the casing. These partition walls 9, 10 are connected together at their upper ends by a connecting wall 12, which is spaced downward from the top wall 13 of the casing 6 to provide a free 95 passage 14 from the inlet 7 to the chamber 15 formed in front of the partition wall 10.

The bottom wall 11 of the casing 6 near its front wall 16 is provided with an opening 17 establishing communication between the front portion of the radiator core and the chamber 15. The rear portion of said core is divided from the front portion at this opening 17 by a partition wall 18. This wall extends clear across the tank 1 from one side to the other and has the casing 6 inserted through it, as shown in Fig. 2. On opposite sides of the casing 6, the partition wall 18 extends up to a plate 19, which extends forward to the front wall of the tank 105 110

- and divides the latter into front and rear sections, as apparent. Said wall 19 has an opening 19^a to permit filling both sections of the core through the filling neck 21. In 5 the detailed arrangement shown in Figs. 2 to 4, it will be noted that the wall 18 is so located that it cuts out from communication with the chamber 15 all but the first two rows of tubes 3.
- 10 Communication between the inlet 7 and the rear section of the core is had through an opening 22 in the bottom wall 11 of the casing 6 between the partition walls 9 and 10 and a port 20 in the partition wall 9.
- 15 This port is controlled by a valve member 23 carried by a stem 24 horizontally arranged and slidably supported in the partition wall 10. For opening and closing the valve 23, there is a thermostat 25 of the 20 bellows type located in the chamber 15 and associated with the valve stem 24.
- The structure shown and described operates as follows. The bellows 25 being contracted by the influence of the cold water 25 in the core 1 holds the valve 23 closed and the rear section of the core 1 cut out of circulation with the inlet 7. When the motor, associated with the radiator, is started, the circulation of the cold water is 30 through the front section or first two rows of water tubes 3 by reason of the fact that the inlet 7 communicates with such section of the core through the passage 14, chamber 15, and opening 17.
- 35 As the rear section of the core is cut out of the circulation, the motor and the cooling medium will warm up more quickly than if the entire core were left in the system, because only a part of the entire amount of 40 water in the core is handled. The heat radiated from the water circulating through the front section of the core will warm up the rear section, and the air drawn through the core by the fan in passing over the 45 warmer front section before the rear section will be warmed before reaching the latter and assist in warming it while the valve 23 remains closed, thus preventing the rear section from freezing in cold weather before 50 the entire radiator is cut in the circulation. As soon as the temperature in the front section is sufficient to expand the bellows 25, the valve 23 will be opened and place the entire radiator in circulation.
- 55 The thermostat device being located within the radiator makes possible the cutting out of one or more sections of the radiator when starting the motor and thus eliminates the chances of freezing the entire radiator 60 as is the case when the thermostatic device is located between the radiator and motor as heretofore. Also having the thermostatic device contained in the radiator not only protects it from injury, but also provides a suitable mounting for the device. My in-

vention also permits the cooling water to be quickly heated when starting the motor and thus avoids the necessity or excuse for the use of radiator curtains or the more expensive radiator shutters as heretofore employed.

While I have shown and described herein in detail a structure of my invention, it is of course to be understood that the details of construction and arrangement of parts 75 may be variously changed and modified without departing from the spirit and scope of my invention.

I claim as my invention:

1. The combination with a radiator for internal combustion engines, of means dividing the radiator core into front and rear circulating sections, and a thermostatic valve device carried by the radiator and leaving the front section of the core in the 80 circulation when the cooling medium is cold, said valve device being operated by the temperature of the cooling medium in the front section for cutting the rear section into 85 and out of the circulation.

2. The combination with a radiator for internal combustion engines, of means dividing the radiator core into front and rear circulating sections, and a thermostatic valve device leaving the front section in the 90 circulation and operated by the temperature of the cooling medium in the front section for cutting the rear section into and out of the circulation, the heat radiated from the front 95 section when warm and the air being warmed in passing over the same before passing over the rear section assisting in warming up the latter before the valve device opens.

3. The combination with a radiator for internal combustion engines having a core 100 provided with a tank and connected conduits for the cooling medium to flow therethrough, of means in said tank dividing the conduits of the core into two circulating sections, and a thermostatic valve device located in said tank, said device leaving one 105 section of the core in the circulation when the cooling medium is cold and operated by the temperature of the cooling medium in that section for cutting the other section into 110 and out of the circulation.

4. The combination with a radiator for internal combustion engines having a core provided with a tank and connected tubes 115 for the cooling medium to flow therethrough, of a partition wall in said tank dividing said tubes of the core into front and rear circulating sections, a casing in said tank and extending through said wall, said casing having an inlet opening and two outlet 120 openings connected therewith, said outlet openings being on opposite sides of said wall to connect the front and rear core sections with said inlet and leaving the front section 125 constantly in the circulation, a valve 130

for controlling the outlet opening to the rear section, and a thermostat device operated by the temperature of the cooling medium in the front section and connected with said valve for opening and closing the same.

5. A thermostatic attachment for radiators, comprising a casing having an inlet opening in one wall, said casing being divided into a plurality of chambers by partition walls, said casing having two outlet

openings, one for each chamber, a valve in one partition wall for controlling the flow from the inlet opening to the adjacent outlet opening, and a thermostat in the chamber having the other outlet opening and connected with said valve for opening and closing the same. 15

In testimony that I claim the foregoing as my invention, I affix my signature, this 20 seventh day of November A. D. 1922.

JAMES H. COOPER.
